UNITED STATES PATENT OFFICE.

HENRY HELLWEG, OF MILWAUKEE, WISCONSIN.

PAPER BOX.

1,123,289.

Specification of Letters Patent.

Patented Jan. 5, 1915.

Application filed February 10, 1913. Serial No. 747,233.

To all whom it may concern:

Be it known that I, HENRY HELLWEG, of Milwaukee, Wisconsin, have invented a Paper Box, of which the following is a specification.

This invention relates to paper or pasteboard boxes, and the object which I have in view is to provide a box with self-contained means for readily and quickly fastening the lid in place on the box-body, or the two telescopic members of the box together, as the case may be, securely and firmly without the aid of a cord; and to provide an improved carrying strap whereby the box may be carried and which will also serve to hold the two members of the box together.

I further aim to provide a pasteboard box which can be used as a cheap and temporary traveling case, and will satisfactorily stand the wear incident to such use.

Heretofore it has been attempted to construct such boxes, but they have had certain disadvantages in practice; the constructions tried have not been practical, either because of their too great expense, too much trouble in opening and closing, or because of parts tearing out in service or the box failing to hold its shape, etc. It is my aim in the present construction to overcome these troubles.

The essential features of my invention by which it is distinguished from all previous inventions consist, first, in a special locking-device for securing the two members of the box together; secondly, in a special mode of applying the handle-strap; and thirdly, in the combination of these two features. In a more elaborate form of the invention, I have also shown how a telescoping box can be arranged to have two or more different extensions, each provided with the essential features of my invention, so that loads of greater or less bulk may be carried in it.

The nature of my invention is best understood from a consideration of the accompanying drawings, which show the most improved form thereof, taken in connection with the following.

In said drawings, Figures 1 and 2 show in plan the two members of a "knock down" telescoping box laid out flat; Figs. 3 and 4 are similar views of the other two pieces which go to form the complete box; Figs. 5, 6 and 7 are respectively a side elevation from the bottom side, a plan, and a transverse median section, of the madeup and

closed box; Figs. 8, 9 and 10 are respectively a plan, a bottom side elevation, and a median transverse section, through another and more elaborate form of box, in closed position, adapted to be adjusted to variable extension; and Fig. 11 is a fragmentary longitudinal section on a larger scale through the upper middle portion of the box, taken in the median line of the handle-strap and showing the latter in elevation.

The reference letters refer each to the same part in each figure of the drawings.

The box as illustrated in the drawing is made up of four elements, to wit, the top member A and bottom member B, which telescope one over the other, the handle-strap C, and the handle-strap locking-piece D, illustrated in Figs. 1 to 4 respectively. For the sake of illustration, the members A and B are illustrated in Figs. 1 and 2 as being of the knock-down type, having on the four sides of the top and bottom sides, a and b, respectively, side-flaps c and end-flaps d, the end-flaps d being detachably secured to the side-flaps c by means of hooked tabs e engaging in angular cuts f formed in the flaps c; but such construction is old and well-known and is in no sense essential to my invention; and in Figs. 5 to 10 inclusive, boxes with fixed corners are shown. Also it is to be understood that while the drawings illustrate a telescoping two-piece box, my invention may be also applied to a box having a lid hinged or otherwise permanently attached to the body. The dotted lines in Figs. 1 and 2 represent the lines along which the pasteboard is creased or scored so as to cause it to fold along these lines.

According to my invention I provide at the middle of each side-flap c of the top-member A, and projecting therefrom, a locking tab g, which has projecting lateral ears h and in some cases preferably a central ear i; these ears being adapted to engage in cuts or slits j, k, formed in the bottom-side b of the bottom-member B. It will be seen therefore from Figs. 5, 6 and 7, that after the top-member A is placed upon the bottom-member B so as to telescope thereover, thus bringing the free edges of the sides c substantially on a level with the bottom-side b of the member B, said flaps g are adapted to fold over upon said bottom-side b and to be held in such position by the en-

gagement of the ears h in the slots j , thus locking the box closed; and it will be observed that this operation is a simple one which can be executed in a moment of time and more conveniently than to tie a cord around the box. In addition it may be said that the lock or fastening so obtained is much stronger than a cord would be, because the tension comes not merely on the center-line of a box as in the case of a cord, which tends to break the two members in the middle unless another cord be passed longitudinally of the box, but the effect of the flaps g is to distribute the strain for a considerable distance on each side of the median plane and thus hold the box better in shape; and of course the flaps g may be made as wide as necessary, having in view the purpose for which the box is designed and the strength and thickness of the material of which it is made. In ordinary-sized boxes, made of usual material, the ears i will not be necessary as the stiffness of the material is sufficient to hold the ears h in place of themselves; but for boxes intended for severe service, or where the width of the flaps g is great, it may be advisable to provide them, to engage in the cuts k , as shown in Figs. 9 and 10.

30 The box as thus far described is complete in itself; but I will now describe my improved carrying means, which is useful by itself and with which the aforesaid lock also coöperates in the manner hereinafter described.

35 In one side c of the member A there is cut a slot l , and in the corresponding side c of the member B there are formed two button-hole slots m m , said buttonhole slots each 40 consisting of a square hole and a cut n at the rear of said hole. The handle-strap C is formed to coöperate with these slots, having on its ends T-heads o , which are too wide to pass through the slots m when seated transversely thereof as shown in Fig. 11, but pass through the slots m when turned longitudinally so as to pass through the cuts n . To facilitate turning one end of the strap C longitudinally through a right angle, it is creased diagonally along the dotted lines q . It will be noted that the width of the slots l and m is the same as that of the strap or middle portion of the member C, and also that the distance between the two slots m m is the same as the length of the slot l , less twice the thickness of the member C; so that when the handle C is in place it is clipped on both sides at its base by the outer and inner edges of the slots l and m respectively, as clearly illustrated in Fig. 8 (from which the members C and D are omitted) and also in Fig. 11.

When the box is put together the handle-
65 strap C is held flat upon the member B until

the latter has passed into the member A and the middle portion of the strap C can enter and pass up through the slot l . It will be now observed that, the ends of the strap being held strictly at right angles to the stress by the ends of the slots l and m as afore described, said straps cannot turn around and thus expose themselves to the liability of being torn off in case the two elements of the box should tend to pull apart. As a further means of holding the strap in this position, and also to hold the strap raised and prevent it from getting under the slot l , I provide the locking-piece D, which as shown is a piece of pasteboard having notches p in the center of the same width as the handle-strap C and adapted to engage the ends thereof in the manner clearly shown in Fig. 6; the distance between the bottoms of said notches p being the same as that between the two slots m . Hence it will be seen that when the handle is set up in the manner shown in Fig. 11 it will hold its place correctly and firmly and will not be in danger of being torn out. Although this handle may be used by itself as a lock, still, however, it would not be satisfactory unless the pasteboard forming the members A and B is of considerable stiffness; because when the box is loaded the pasteboard has a tendency to bülge, and in particular the sides c tend to separate when the box is carried by the handle-strap C; so that the strain brought upon the strap C is not a simple shear upon a plane dividing the two flaps through which it passes, but an oblique tearing action. Consequently it is necessary for effectiveness that the side c of the outer member A (or lid) be held closely down upon the side c of the member B (or body), and this function is fulfilled by my lock or fastening g .

My improved construction also admits providing a telescoping box with various degrees of overlap so as to provide for different sizes of package; and this more elaborate construction is illustrated in Figs. 8, 9 and 10. In this construction the top or outer member A' of the box is provided in its upper side c' with two parallel slots l' of the same shape as the slot l ; the corresponding side c' of the member B' being provided with the slots m the same as before. Also, in place of the flaps g there are provided flaps g' which are longer and are scored at two or more places for folding over the edge of the member B'; and in the bottom-side b' of the member B' are formed two or more sets of slots j k so placed as to be adapted to receive the ears h i of the flaps g' in the various positions of the latter, corresponding with the different degrees of the extension of the box. Of course it is understood that, while only two extensions are shown in the drawing, as

many more may be used as circumstances require and the depth of the telescoping-sections makes practical or advantageous.

Having thus described my invention, 5 what I claim as new and desire to secure by Letters Patent is:

1. A telescoping box comprising a top-member and a bottom-member adapted to telescope one over the other, said top-member having on the free edges of opposite sides a pair of projecting flaps which are adapted to fold over and lie flat upon the bottom-face of said bottom-member; together with means for fastening said flaps 10 in said position.
2. In a telescoping box, the combination with a bottom-member and top-member which telescope one over the other of a pair of flaps projecting from the free edges of the telescoping sides of said top-member, 15 said flaps being creased along several lines so as to fold along any of said lines over upon the bottom-face of said bottom-member; and a pair of oppositely directed ears 20 carried by each flap; said bottom-member having formed in the bottom side thereof several sets of slots adapted to receive said ears in any of the various positions of extension of the box provided for by the different folding-lines of said flaps.
3. In a paper-box, the combination with members which overlap when in the closed position of the box, of a handle-strap having T-headed ends; said overlapping members having formed therein registering slots 25 through which the shank of said strap passes; the under one of said overlapping members having two buttonhole slots and the upper one thereof having a single closed slot of substantially the same length as the distance between the two buttonhole slots.
4. In a paper-box, the combination with members which overlap when in the closed position of the box, of a handle-strap having T-headed ends; said overlapping mem- 30

bers having formed therein registering slots through which the shank of said strap passes; the under one of said overlapping members having two buttonhole slots and the upper one thereof having a single closed slot of substantially the same length as the distance between the two buttonhole slots; in conjunction with a locking-piece comprising a plate-member having its ends notched to engage the ends of the shank of 50 said handle-strap and acting as a strut to hold said ends against the ends of said closed slot in the upper overlapping-member.

5. A paper-box having two members 60 which overlap at the free edges in the closed position of the box, said overlapping members having registering slots, and a handle-strap having T-headed ends passing through said slots; in conjunction with a 65 flap on the free edge of the outer overlapping member adapted to fold over the bottom of the box and having means for fastening it in said position.

6. A paper-box having two members 70 which overlap at the free edges in the closed position of the box, said overlapping members having registering slots, and a handle-strap having T-headed ends passing through said slots; in conjunction with a 75 flap on the free edge of the outer overlapping member adapted to fold over the bottom of the box and having means for fastening it in said position, and a handle-locking-piece comprising a plate of flexible 80 material notched at its ends to engage around the ends of the shank of said handle-strap and hold them apart.

In witness whereof I have hereunto set my hand in presence of two witnesses.

HENRY HELLWEG.
